ADVANCING REEL

William G. Esmond, Cumberland, Md., assignor
to Celanese Corporation of America, a corpora-
tion of Delaware

Application June 21, 1947, Serial No. 756,179

10 Claims. (Cl. 28—71.7)

1

This invention relates to apparatus employed in the manufacture of artificial silk filaments, thread, yarn and the like, hereinafter referred to as "yarn," and relates more particularly to a reel adapted to advance helices of yarn in an axial direction. The yarn may be subjected to a treatment with a fluid medium or mediums during the movement of the helices of yarn along the reel.

An object of this invention is the provision of an improved advancing reel characterized by its simplicity and strength of construction.

Another object of this invention is to provide an improved advancing reel embodying a plurality of bars which are angularly spaced with respect to each other, the angular spacing being fixed and equal and which bars are divided into two cages adapted for interdigitating movement.

A further object of this invention is to provide an improved advancing reel in which the interdigitating and yarn advancing motions of the bars of the reel are effected by means of solenoids exerting magnetic attraction against an opposing force exerted by a suitable spring.

Other objects of the present invention, together with certain details of construction and combinations of parts, will appear from the following detailed description.

In the drawings wherein a preferred embodiment of this invention is shown,

Fig. 1 is a vertical sectional view of the reel of this invention,

Fig. 2 is a detail view, on an enlarged scale, of the commutator strip arrangement,

Fig. 3 is a detail view of one of the solenoids imparting to the bars interdigitating motion,

Fig. 4 is a cross-sectional view taken on line 4—4 in Fig. 3,

Fig. 5 is an elevational view showing a bar of the reel arranged on its solenoid,

Fig. 6 is an end elevational view of the bar and solenoid arrangement shown in Fig. 5, and

Fig. 7 is a wiring diagram for the solenoids imparting interdigitating and advancing motions to the bars on the reel.

Like reference characters indicate like parts throughout the several views of the drawings.

As is well known, reels of the type of the reel of the instant invention which are adapted to advance helices of yarn axially comprise a plurality of spaced bars arranged circumferentially about an axis. These bars are divided into equal parts to form two cages, the bars of one cage being caused to reciprocate vertically and horizontally in a different order than the bars of the other cage.

2

Referring now to the drawings for a detailed description of the advancing reel of this invention, the reel comprises a plurality of bars, preferably sixteen per cage, arranged circumferentially about shaft 8 driven by any suitable means (not shown). Two of such bars 9 and 11 are shown.

The bars 9 and 11 which alternate with each other around the reel are substantially similar in structure and comprise an elongated hollow member 12 having fixed at one end thereof a cylindrical projection 13 of any suitable magnetic material. The bars 9 and 11 are supported in annular brackets 14 attached to one end of flat springs 15, the other ends of said flat springs being attached to collars 16 fixed to shaft 8 for rotation therewith.

Each of the bars 9 and 11 telescopes an oval-shaped solenoid 17 and 17', respectively, supported on shelves 18 extending between and carried by spiders 19 and 21 fixed to and rotated by shaft 8. The shelves 18 and bars 9 and 11 are provided with projections 22 for holding and retaining expansible springs 23 in position between the shelf and the bar. These springs 23 are adapted to maintain the bars in extended position relative to the shelves.

The shaft 8 is rotatably mounted in a bearing bracket 24 provided with openings 25 through which bolts are adapted to pass for attachment to a suitable member (not shown) for supporting the reel structure firmly and rigidly. The inner end of the bearing bracket is provided with a flange 26 on the inner face of which is mounted the commutator strip arrangement shown in Fig. 2 and generally indicated by reference numeral 21. Brushes 28W, 28X, 28Y and 28Z, which are adapted to be in contact with the commutator strips, are mounted in one face of a drum 29 which is fixed to and rotates with shaft 8 and which also carries circumferentially thereof a solenoid 31 thereon for each of the bars 9 and 11. Each projection 13 of the bars extends into its adjacent solenoid 31 or 31'.

45 The interdigitating and yarn advancing motions of the yarn advancing reel of this invention are accomplished by means of the solenoids 17, 17', 31 and 31' exerting magnetic attractions on the bars 9 and 11 and the projections 13, each bar 9 of one cage and each bar 11 of the other cage being actuated by its solenoids 17 and 31. The solenoid 17 causes the in-and-out movement or the "interdigititation" of the bar. The solenoid 31 controls the lateral movement of the bar which 55 causes the yarn in contact with the bar to be ad-

vanced. Each solenoid of the reel is grounded on one side and on the other is connected to a brush in contact with the commutator strips 27 mounted on flange 26. Thus, all of the solenoids 17 cooperating with arms 9 of one of the cages are connected to brushes 28W (only one of which is shown, there being one brush for each solenoid or two brushes per bar) in contact with the innermost commutator strip W; all of the solenoids 17' cooperating with arms 11 of the other of the cages are connected to brushes 28X in contact with commutator strip X; all of the solenoids 31 cooperating with projections 13 of bars 9 are connected to brushes 28Y in contact with commutator strip Y; and all of the solenoids 31' cooperating with projections 13 of bars 11 of the other cage are connected to brushes 28Z in contact with commutator strip Z. The numbers shown on each block of each commutator strip represents the potential of that block in volts. These voltages are obtained from a transformer 32.

The interdigitation movements of the bars 9 comprising one of the cages is as follows: As the brush 28W connected to the solenoids 17 travels around commutator strip W, in the position of 0 voltage, the bar is fully extended. As the voltage increases to 1, 2, 3, 4 and 5 volts, the bar is caused to be drawn in by solenoids 17 against the action of springs 23. As the voltage then decreases to 4, 3, 2, 1 and 0 volts, the springs 23 cause the bar to be extended to its original outermost position. The bars 11 of the other cage are interdigitated in exactly the same manner as the bars 9 but 180° out of phase therewith.

The advancing motion of the bars is effected as follows: The solenoids 31 exert no attraction on the projections 13 of bars 9 when their brushes 26Y rest upon the portion of commutator strip Y with 0 voltage. As each brush 28Y progresses clockwise around the commutator strip Y, the voltage increases 1, 2, 3, 4, 5, etc., up to 18 volts. This causes the bar to advance uniformly against the action of flat springs 15. The advancing motion of the bars 9 is arranged to start before the bars are fully extended and in contact with the yarn and is arranged to continue until after the bars are withdrawn and away from the yarn. After the bars are withdrawn, the voltage on the solenoids 31 cooperating with the projections 13 on bars 9 drops from 18 to 15, 12, 9, 6, 3 and 0 in order to permit the springs 15 to return the bars for the next advancing motion. The bars 11 of the other of the cages are advanced and returned in exactly the same manner as the bars 9 except that the advance and return are 180° out of phase with the advance and return of the bars 9.

A flange housing 33 is attached to drum 29 for the purposes of protecting the commutator strips and brushes from dust and moisture.

It is to be understood that the foregoing detailed description is given merely by way of illustration and that many variations may be made therein without departing from the spirit of my invention.

Having described my invention, what I desire to secure by Letters Patent is:

1. A reel for advancing helices of yarn axially, comprising a rotatable shaft, a plurality of longitudinally extending bars for carrying the yarn along the reel mounted on said shaft for rotation therewith, and separate electrical means for each bar for reciprocating said bars individually.

2. A reel for advancing helices of yarn axially, comprising a rotatable shaft, a plurality of

spaced, circumferentially arranged, longitudinally extending bars for carrying the yarn along the reel mounted on said shaft for rotation therewith, and separate electrical means for each bar for reciprocating said bars individually.

3. A reel for advancing helices of yarn axially, comprising a bearing, a rotatable shaft journaled in said bearing, a plurality of spaced, circumferentially arranged, longitudinally extending bars for carrying the yarn along the reel mounted on said shaft for rotation therewith, and means including a plurality of solenoids cooperating with said bars for reciprocating each of said bars radially and axially in a predetermined order.

15 4. A reel for advancing helices of yarn axially, comprising a bearing, a rotatable shaft journaled in said bearing, a plurality of spaced, circumferentially arranged, longitudinally extending bars for carrying the yarn along the reel mounted on said shaft for rotation therewith, means including a plurality of solenoids cooperating with said bars for reciprocating each of said bars radially and axially, and a commutator strip for energizing said solenoids in predetermined order.

25 5. A reel for advancing helices of yarn axially, comprising a bearing, a rotatable shaft journaled in said bearing, a plurality of spaced, circumferentially arranged, longitudinally extending bars for carrying the yarn along the reel mounted on said shaft for rotation therewith, means including a plurality of solenoids cooperating with said bars for reciprocating each of said bars radially and axially, and a plurality of commutator strips for energizing said solenoids.

35 6. A reel for advancing helices of yarn axially, comprising a bearing, a rotatable shaft journaled in said bearing, a plurality of spaced, circumferentially arranged, longitudinally extending bars for carrying the yarn along the reel mounted on said shaft for rotation therewith, means including a plurality of solenoids cooperating with said bars for reciprocating each of said bars radially and axially, and a plurality of commutator strips of varying voltage for energizing said solenoids.

40 7. A reel for advancing helices of yarn axially, comprising a bearing, a rotatable shaft journaled in said bearing, springs carried by said shaft for rotation therewith, a plurality of spaced, circumferentially arranged, longitudinally extending bars for carrying the yarn along the reel mounted on said springs, spiders mounted on said shaft for rotation therewith, solenoids carried by said spiders for operating said bars, springs operatively connected to said bars, a plurality of solenoids mounted on said shaft, a plurality of commutator strips for energizing said solenoids, and brushes electrically connected to said solenoids and said commutator strips whereby rotation of said reel effects the radial and axial reciprocation of said bars.

45 8. A reel for advancing helices of yarn axially, comprising a bearing, a rotatable shaft journaled in said bearing, flat springs carried by said shaft for rotation therewith, a plurality of spaced circumferentially arranged, longitudinally extending bars for carrying the yarn along the reel mounted on said flat springs, spiders mounted on said shaft for rotation therewith, solenoids carried by said spiders for operating said bars, springs operatively connected to said bars, a plurality of solenoids mounted on said shaft, a plurality of commutator strips of varying voltage for energizing said solenoids mounted on said bearing, and brushes electrically connected to said solenoids and said commutator strips whereby ro-

tation of said reel effects the radial and axial reciprocation of said bars.

9. A reel for advancing helices of yarn axially, comprising a bearing, a rotatable shaft journaled in said bearing, a plurality of spaced, circumferentially arranged, longitudinally extending bars for carrying the yarn along the reel mounted on said shaft for rotation therewith, means including a plurality of solenoids cooperating with said bars for reciprocating each of said bars radially and axially, and a plurality of concentric commutator strips of varying voltage for energizing said solenoids.

10. A reel for advancing helices of yarn axially, comprising a bearing, a rotatable shaft journaled in said bearing, springs carried by said shaft for rotation therewith, a plurality of spaced, circumferentially arranged, longitudinally extending bars for carrying the yarn along the reel mounted

on said springs, spiders mounted on said shaft for rotation therewith, solenoids carried by said spiders for operating said bars, springs operatively connected to said bars, a plurality of solenoids mounted on said shaft, a plurality of concentric commutator strips for energizing said solenoids, and brushes electrically connected to said solenoids and said commutator strips whereby rotation of said reel effects the radial and axial reciprocation of said bars.
